FURNITURE GLIDE

John C. Rasor and Norman A. Johnson, Youngstown, Ohio, assignors to The General Fireproofing Company, Youngstown, Ohio, a corporation of Ohio

Filed July 23, 1964, Ser. No. 80,986

Term of patent 14 years

(Cl. D33—1)

FIG. 1.

FIG. 2.

FIG. 3.

FIG. 4.

FIG. 5.

FIG. 6.

FIG. 7.

FIG. 8.

FIGURE 1 is a top perspective view of the furniture glide embodying our new design.

FIGURE 2 is a top perspective view of the other side of the furniture glide shown in FIGURE 1.

FIGURE 3 is a top plan view of the furniture glide shown in FIGURES 1 and 2.

FIGURE 4 is a side elevation of the furniture glide.

FIGURE 5 is an end elevation of the furniture glide.

FIGURE 6 is a side elevation illustrating the side opposite to that shown in FIGURE 4.

FIGURE 7 is a sectional view taken on the line 7-7 of FIGURE 4.

FIGURE 8 is a top perspective view of the furniture glide as applied to a furniture base member.

The phantom line showing of a furniture base fragment in FIGURES 7 and 8 is for illustrative purposes only.

We claim:

The ornamental design for a furniture glide, as shown and described.
